AUTOMATIC STOP FOR RAILROAD ROLLING STOCK

Leonard Charles Brothers, Lewisberry, and
William Arthur Sheetz, Harrisburg, Pa.

Application November 26, 1947, Serial No. 788,303

5 Claims. (Cl. 104—257)

(Granted under the act of March 3, 1883, as
amended April 30, 1928; 370 O. G. 757)

1

This invention relates to an automatic wheel chock, and has for an object to provide an improved means for automatically chocking the wheels of a railroad vehicle to limit and stop its movement in a desired direction, yet release it for movement in the opposite direction, without the need for manual operation in placing the chock in position, while at the same time, leaving the rail surface free of any obstruction when the railroad car or locomotive is not in position.

Many shop and factory floors have railroad tracks located therein whereon railroad cars and locomotives come from time to time, to deliver raw or partly complete material, and to pick up more completely finished material for transportation elsewhere. At the same time, the floor surface through which the tracks extend must be kept clear of obstructions for the safe passage of the personnel or of surface vehicles, hence it is not desirable to place permanent chocks in position for limiting the travel of the railroad vehicle, and it therefore has been the custom to manually place temporary chocks in position wherever needed, with the attendant risk to the personnel performing such operation, and the additional danger that the chock may not be placed in position when needed, due to human fallibility, with the resultant danger that shop and factory equipment may be damaged by "drifting" rail vehicles.

It is an object of this invention to eliminate such danger both to personnel and to equipment by providing an automatic chock that remains below floor level when the rail car is not present, and wherein the action of the rail car in arriving is sufficient to bring the chock into operative position to limit the further advance of the rail car, and then, when the rail car is withdrawn, it automatically retracts the chock back to below floor level.

With the foregoing and other objects in view, as will hereinafter become apparent, this invention comprises the combinations, constructions and arrangement of parts hereinafter disclosed, set forth and illustrated on the accompanying drawings, wherein,

Fig. 1 is a perspective view of the automatic chock of this invention in operative chocking position;

Fig. 2 is an exploded isometric view;

Fig. 3 is a side elevation, and

Fig. 4 is a sectional view on line 4—4 of Fig. 3.

Fig. 5 is a plan view of the chock.

There is shown at 10 a conventional track rail having its wheel carrying surface 11 located

2

at the same level as the shop floor level. The automatic wheel chock of this invention includes a wheel chock 12 adapted to be placed in wheel stopping position on the rail surface 11 to stop the railroad car wheel and prevent the car from passing thereby. This invention is so contrived that the first wheel 14 passes the chock 12 and operates the chock 12 automatically to prevent the second wheel 15 from passing, and then the first wheel 14 on repassing in the opposite direction causes the chock 12 to be withdrawn from the rail surface 11 and drop to or below the floor level, ready for immediate and automatic operation the next time a rail car wheel passes thereover.

The automatic chock includes a supporting plate 16 which is welded or otherwise secured against the rail web 17 in an appropriate location. This plate 16 is provided with a pair of spaced steps 18 leading to a depressed floor 20. Angularly secured, as by welding, to the side of the plate 16 away from the rail 10 and alongside each step 18 are a pair of sheets 21 extending upwardly to about the top level of the plate 16.

The wheel chock 12 is shaped as shown, having an arcuate surface 22 provided with a pair of bronze bearing pads 23 against which the second wheel 15 rests in stopping position. The chock 12 is integrally formed with an offset depending flange 24 extending down below the bottom of its arcuate surface 22, and welded or otherwise secured to the inner surface of this depending flange 24 is a roller 25 arranged to have its ends bear on the steps 18 behind the angular sheets 21. The top of this flange 24 is also provided with an arcuate surface 26, concentric with but of greater radius than arcuate surface 22 and is intended to receive the rail wheel flange 27. The floor 20 is at a level to permit the flange 24 to overlie it when the chock is swung down.

Extending from the top of the end of the chock 12 is an angular toe 28 having its rear surface 30 forming an angle of about 130° with the sides of the chock 12. Pivoted on a stud 31 extending through a stud support 32 into the plate 16 rearwardly of the chock 12 is an actuating lever 33, shaped as shown, with a cylindrical arm 34 arranged to move along the outer surface 35 of the depending flange 24 of wheel chock 12, and a bowed leaf arm 36 having its upper surface no higher than the floor or rail surface 11.

The shop floor will be recessed between the tracks just enough to receive the chock 12 in the reclining position, and the chock 12 is of

such thickness that its inner surface, when in upright position, is at or slightly below floor level when in reclining position. In addition, a similar wheel chock, a duplicate of this, but reversed right for left, may be placed on the other rail track at the corresponding point on such other track.

In operation, the first rail wheel 14 passes the location of the wheel chock 12 in reclining position without touching any part thereof, passes over the pivot stud 31 and its flange rides on and depresses the bowed leaf arm 36 of actuating lever 33, causing the cylindrically shaped arm 34 to move up along the outer surface 35 of wheel chock 12. This pivots the chock 12 about its roller 25 and raises it to a position to rest on the rail surface 11 in time to chock or stop the second wheel 15 and prevent its passage thereby. When the rail car is being withdrawn, the first wheel flange again passes over the bowed lever arm 36 in the opposite direction, which, beyond having its actuating arm 34 raised up and then dropped, performs no function. The flange of the first wheel 14 then abuts and rides along the angular surface 30 of the chock toe 28, causing the chock 12 to pivot over on its roller 25 and drop over on its side, away from the obstructing position, but resting over the actuating lever arm 34 ready to be again raised into chocking position when next a rail wheel passes thereover. As a further feature, it will be noted that the construction is such that the chock 12 and its roller 25 can be removed and replaced by merely lifting it out of the recess between the bearing steps 18, thus enabling the part receiving most wear and strain to be inexpensively replaced when necessary, without disturbing the remaining parts, and at practically no labor expense.

Other modifications and changes in the number, construction and arrangement of the parts may be made by those skilled in the art without departing from the nature of this invention within the scope of what is hereinafter claimed.

The invention described herein may be manufactured and used by or for the Government of the United States of America for governmental purposes without the payment of any royalties thereon or therefor.

Having thus set forth and disclosed the nature of this invention, what is claimed is:

1. A rail wheel chock apparatus comprising a wheel chock, means for pivoting said wheel chock along side a rail in fixed position longitudinally thereof, means actuatable by a rail wheel passing thereover to pivot said chock to a position obstructing the next rail wheel attempting to pass such position, said actuatable means including an actuating lever pivoted along side the rail, said lever having one arm arranged to be depressed by the first rail wheel passing thereover and a second arm arranged under the chock to raise the chock to obstructing position against a second rail wheel as said first arm is depressed.

2. A rail wheel chock apparatus comprising a wheel chock, means for pivoting said wheel chock along side a rail, means actuatable by a rail passing thereover to pivot said chock to a position obstructing the next rail wheel attempting to pass such position, said actuatable means including an actuating lever pivoted along side the rail, said chock pivoting means including a pivot roller having its longitudinal axis extending parallel to the rail, a supporting plate secured along side the rail, a bearing for said roller formed in said supporting plate comprising a pair of longitudinally

spaced apart steps and means secured to said plate holding said roller against transverse displacement therefrom, but open at the top and permitting vertical removal and replacement.

3. A rail wheel chock apparatus comprising a wheel chock, means for pivoting said wheel chock along side a rail, means actuatable by a rail wheel passing thereover to pivot said chock to a position obstructing the next rail wheel attempting to pass such position, said actuatable means including an actuating lever pivoted along side the rail, said chock pivoting means including a pivot roller having its longitudinal axis extending parallel to the rail, a supporting plate secured along side the rail, a bearing for said roller formed in said supporting plate comprising a pair of longitudinally spaced apart steps and means secured to said plate holding said roller against transverse displacement therefrom, but open at the top and permitting vertical removal and replacement, said actuating lever including means pivoting said lever to said supporting plate, said lever comprising an arm extending from one side of its pivot and arranged to rest under said wheel chock when in reclining position and to raise said chock to wheel obstructing position, and an arcuately bowed arm extending from the other side of its pivot and arranged to be depressed by a rail wheel as it passes thereover to raise said arm and its supported wheel chock.

4. An automatic rail wheel chock comprising a wheel chock, means for pivoting said wheel chock along side a rail, means actuatable by a rail wheel passing thereover to pivot said chock to a position obstructing the next rail wheel attempting to pass such position, said actuatable means including an actuating lever pivoted along side the rail, said chock pivoting means including a pivot roller having its longitudinal axis extending parallel to the rail, a supporting plate secured along side the rail, a bearing for said roller formed in said supporting plate comprising a pair of longitudinally spaced apart steps and means secured to said plate holding said roller against transverse displacement therefrom, but open at the top and permitting vertical removal and replacement, said actuating lever including means pivoting said lever to said supporting plate, said lever comprising an arm extending from one side of its pivot and arranged to rest under said wheel chock when in reclining position and to raise said chock to wheel obstructing position, and an arcuately bowed arm extending from the other side of its pivot and arranged to be depressed by a rail wheel as it passes thereover to raise said arm and its supported wheel chock, said wheel chock including a wheel chocking forward arcuate surface and an angular rear surface arranged, when in wheel obstructing position, to extend across the path of a rail wheel approaching from the rear side and be contacted by such approaching wheel to pivot said chock from wheel obstructing position to reclining position resting on said actuating lever arm ready for a subsequent automatic wheel chocking actuation.

5. A rail wheel chock apparatus comprising a wheel chock, means for pivoting said wheel chock along side a rail with its upper surface no higher than that of the rail, means actuatable by a rail wheel passing thereover to pivot said chock to a position obstructing a rail wheel attempting to pass such position, said actuatable means including an actuating lever pivoted along side the rail, said lever having one arm no higher than the uppermost rail surface and arranged to be

depressed by the flange of a rail wheel passing thereover and a second arm arranged under the chock to raise the chock to obstructing position against a rail wheel as said first arm is depressed.
